METAL FLUME

Roy M. Soper, Kansas City, Mo.

Application November 26, 1937, Serial No. 176,533

4 Claims. (Cl. 61—15)

This invention relates to semicircular metal flumes for conveying water and more particularly to improved methods of supporting the sections forming the flume, and connecting and sealing the connections of the sections against leakage. This invention further relates to means to prevent the water from being splashed and blown out of the flume.

Semicircular metal flumes are old, but the connections of the sections and the method of sealing against leakage have been complicated and in some constructions very obstructive to the flow of water. The supports of the connections of main sections have not been rigidly supported in a true semicircular form so as to insure a perfect seal against leakage, and water has been lost by being splashed and blown from the flume.

The present invention has provided, an improved flume with an internal surface free and unobstructed to the flow of water, inexpensive and efficient seals against leakage at the connections of the sections, a rigid and true semicircular support at the connection of all main sections of the flume, and an antisplash flange along each open edge of the flume to prevent water from being splashed and blown from the flume. The intermediate flume sections have been provided with means to develop the bottom steel tension, and prevent sagging at the connections, and to prevent creeping of the packing.

Another object of the present invention is to provide a flume construction that is easily made and held in a rigid true semicircular shape to retain the intended full capacity of the flume. The ends of the flumes are turned back and lapped over the outside of the flume sheet when in a flat shape and then formed to the semicircular shape. This method is also used in forming the intermediate bands that support the intermediate sections of flumes and is a very simple, economical and rigid construction. The frame work that supports the flume is welded into a metal truss that prevents undue distortion to the shape of the flume and assures full calculated capacity. The distortion of most flumes being caused by excessive tension on the bolts to insure sealed joints.

With these and other objects in view, the invention consists of the features of construction, combinations and arrangements of parts as hereinafter set forth and more particularly pointed out in the appended claims, the accompanying drawings illustrating a form of the improved flume that is manufactured and marketed with

satisfaction to the manufacturer and consumers.

In the drawings:

Fig. 1 is a view in side elevation of one main section of the improved flume and a fragmentary view of an adjoining main section at each end thereof.

Fig. 2 is a vertical cross section of the flume on line 2—2 of Fig. 1.

Fig. 3 is a vertical cross section of the flume on line 3—3 of Fig. 1.

Fig. 4 is a fragmentary plan view of the flume.

Fig. 5 is an enlarged fragmentary sectional view on line 5—5 of Fig. 3.

Fig. 6 is an enlarged fragmentary sectional view on line 6—6 of Fig. 2.

In Fig. 1 is illustrated one main section of the improved flume, comprising end sections 1, intermediate section 2, and fragmentary views of adjacent end sections 1. It will be understood that the flume comprises a succession and repetition of main sections, and that the number of intermediate sections in each main section will always depend on the distance between supports particularly the size of the flume, and the thickness of the metal employed to form the flume.

All the main sections of the flume comprising end sections 1 and intermediate section 2 are formed in semicircular shape as shown, and both upwardly disposed edges are turned inwardly in a meeting direction approximately in the direction of the radial axis of the semicircular shape forming the horizontally disposed flanges 3, which terminate in the downwardly disposed flanges 4. The flanges 3 and 4 form a continuous antisplash flange along each upwardly disposed edge of the flume, from end to end thereof.

The adjoining ends of all the sections 1 and 2 are secured by the tie plates 5 resting on the flanges 3 and the tie bars 6 resting on the tie plates, the bolts 7 passing through the flanges 3 and the tie plates, and the bolts 8 passing through the flanges 3 the tie plate 5 and the tie bar 6, the bolts fitting loosely according to common practice in the flanges 3 the tie plates 5 and the tie bars 6 being sufficient for expansion and contraction.

The ends 9 of the main sections, comprising end sections 1 and intermediate section 2, rest on the compressible packing 10 on the main tie band 11. The tie band 11 is welded integral with the supporting frame comprising horizontal portion 12, vertical portions 13, horizontal portion 14 and angular brace portions 15, and the horizontal portion 14 and the tie band 11 are welded together at 16, so that the frame sup-

ports the flume sections 1 rigidly in a semicircular position preventing distortion of the flume when the band 11 is tightened. The supporting frame rests on the foundation timber 17 and is secured thereto by the bolts 18 passing through the horizontal portion 14 of the frame and through the timber.

The draw bolts 19 connect the draw band 11 with the tie plates 5 and tie bar 6 and bind the ends 9 of the flume sections 1 tightly upon the packing 10 and draw band 11 so that the flume sections are held rigidly in place as shown and perfectly sealed against leakage of water between the ends 9 of the main sections.

15 The abutting ends 20 of the flume sections 1 and 2 all of which are duplicate are folded outwardly and around the outer side of the semicircular shape of the sections as shown particularly in Fig. 5 forming the oppositely disposed shoulders 21. The intermediate draw bands 22 are folded as also shown in Fig. 5 forming the inwardly facing shoulders 23, and the draw bands 22 are placed around the flume sections as shown with the outwardly disposed shoulders 21 just 25 filling the distance between the inwardly disposed shoulders 23, the compressible packing being arranged between the bands and the flume sections.

The draw bolts 24 shown welded to the bands 22 30 pass upwardly through the tie plates 5 and tie bars 6 thus drawing the bands tightly upon the packing, the shoulders 21 and 23 preventing the flume sections 1 and 2 from spreading apart and sagging where connected.

35 The integrally welded supporting frame comprising the main tie band 11, short horizontal portions 12, vertical portions 13, long horizontal base portion 14, angular braces 15 and weld 16, in connection with the tie plates 5, tie bar 6 and bolts 40 binding the parts together, form a rigid efficient and inexpensive support, tie and seal for the connection of the main sections of the flume.

The construction just described of the supporting frame provides for the abutting connection of the main sections of the flume and the employment of flat packing, and insures a dependable flume with free and unobstructed joints so the water can flow freely therein.

45 The intermediate connections are so constructed that flat packing is employed, the shoulders 21 and 23 secure the packing in place against slippage from expansion and contraction, and sagging of the sections at the intermediate connections is prevented except the deflection

due to compression and tension. The intermediate connection of sections comprises abutting sections and there is no obstruction to the flow of water.

The anti-splash flange prevents loss of water from splashing out and from being blown out of the flume.

Having described my invention, what I claim as new and desire to secure by Letters Patent, is:—

1. A sheet metal flume of semicircular shape and comprising longitudinally disposed abutting sections provided with an internally disposed flange along each longitudinal edge of each section, said sections connected to tie plates resting on said flanges, a transversely disposed tie bar connecting each pair of tie plates, a flat compressible packing overlapping the ends of each pair of abutting sections, a draw band around the outwardly facing side of said packing, and bolts connected to said draw bands and passing upwardly through said tie plates and binding said bands and said packing to said sections. 15

2. A semicircular flume comprising end sections and intermediate sections, said end sections abutting, a flat compressible packing overlapping the ends of said abutting sections, a draw band outside of said packing, a frame securing said draw band rigidly in a semicircular shape, and bolts binding said sections to said compressible pack- 20 ing and said draw band. 25

3. A semicircular flume comprising end sections and intermediate sections, said intermediate sections abutting and external shoulders formed on said intermediate sections, said shoulders facing from the abutting ends of said sections, a flat compressible packing arranged immediately below said flume sections between said shoulders, and a draw band with internal facing shoulders meshing over said external shoulders and binding said 35 packing to said flume sections. 40

4. A semicircular flume comprising end sections and intermediate sections, said end sections connected by a supporting frame with a horizontal portion resting on the usual foundation, said frame rising upwardly from said horizontal portion on each side of said flume sections and then forming a semicircular shaped draw band, said draw band connecting to the horizontal portion at the low extremity thereof, compressible pack- 45 ing on said draw band, and draw bolts arranged to bind said flume sections eighty to said frame with the packing arranged there between. 50
